UNITED STATES PATENT OFFICE

123,667

DESIGN FOR A VANITY BAG

Maude Plunkett Collester, Bronxville, N. Y., assignor to I. B. Kleinert Rubber Company, New York, N. Y.

Application September 23, 1940, Serial No. 95,298

Term of patent 7 years

To all whom it may concern:

Be it known that I, Maude Plunkett Collester, a citizen of the United States, residing at The Towers, Bronxville, in the county of Westchester and State of New York, have invented a new, original, and ornamental Design for a Vanity Bag, of which the following is a specification, reference being had to the accompanying drawing forming a part thereof.

Fig. 2 is a top view thereof.

Fig. 3 is a top view thereof with the cover in open position.

I claim:

The ornamental design for a vanity bag, as shown.

MAUDE PLUNKETT COLLESTER.
